INVENTOR:

Guido Perera
BY Aladar Hamburger

ATTORNEY

UNITED STATES PATENT OFFICE.

GUIDO PERERA, OF NEW YORK, N. Y.

SAFETY MATCH-BOX.

1,236,758.

Specification of Letters Patent. Patented Aug. 14, 1917.

Application filed March 8, 1917. Serial No. 153,466.

To all whom it may concern:

Be it known that I, GUIDO PERERA, a subject of the King of Italy, residing at New York, in the county and State of New York, 5 have invented new and useful Improvements in Safety Match-Boxes, of which the following is a specification.

This invention relates to a safety match box and has as its object to provide a match box with a surface on which the matches are adapted to be lighted, so arranged that it can be used only when the match box is closed and, when the latter is opened sufficiently to take out matches therefrom, the 10 surface on which the match may be lighted is hidden, thereby preventing accidents which very often happen when a match is struck while the match box is open and the whole contents of the box flare up.

20 In the accompanying drawing:

Figure 1 is a perspective view of my device, seen from the bottom, in its closed position;

Fig. 2 is a similar view, with the box 25 opened;

Fig. 3 is a cross sectional view of the match box, the section being taken on the line 3—3 of Fig. 1, looking in the direction indicated by arrows.

30 The same part is designated by the same reference character throughout the several views.

Referring to the drawing by numerals; 4 is the box proper such as is commonly used, 35 having four sides and a bottom and open at the top. 5 is an outer cover or sleeve in

which the box proper 4 is adapted to slide freely back and forth, the matches contained therein being accessible only when one end of the box proper is pulled out of the sleeve 5 in about the proportion seen in Fig. 2.

40 Thus far the construction of my match box is the same as of those in use at present, but it differs therefrom in the location of the striking or lighting surface which in ordinary match boxes is applied to the side of the sleeve 5. This surface is either rough or chemically prepared to light a match when in frictional contact therewith and, in my device, it is placed on the backside of the bottom of the box proper 4, as at 7, 45 across thereof, at its longitudinal center. A corresponding portion is cut out of the sleeve 5, as at 6, with which portion the lighting surface 7 registers in the closed position of 50 the box, as shown in Fig. 1, whereas when the box is open, as in Fig. 2, the lighting surface 7 disappears under the sleeve 5, thereby accomplishing the result which I 55 have described as the object of my invention.

60 I claim:—

A match box having telescoping inner and outer members, the inner member being provided with a match striking surface and the 65 outer having, intermediate of its length, an opening which is substantially co-extensive with, and is adapted for registration with and exposure of said match striking surface only when the box members are in their 70 closed relative positions.

GUIDO PERERA.
